UNITED STATES PATENT OFFICE

130,993

DESIGN FOR A DENTAL FORCEPS

William G. Lewis, Iola, Kans.

Application November 3, 1941, Serial No. 104,002

Term of patent 7 years

To all whom it may concern:

Be it known that I, William G. Lewis, a citizen of the United States, residing at Iola, in the county of Allen and State of Kansas, have invented a new, original, and ornamental Design for a Dental Forceps, of which the following is a specification, reference being had to the accompanying drawing, forming part thereof:

Figure 1 is a side elevational view of a dental forceps showing my new design.

Figure 2 is a top plan view thereof, and
Figure 3 is a front view thereof.

I claim:

The ornamental design for a dental forceps, as shown.

WILLIAM G. LEWIS.
